A. Randolph, Jr.
Attorney

UNITED STATES PATENT OFFICE.

RILEY M. DODD AND JOSEPH A. McVAY, OF TORRANCE, CALIFORNIA.

MOTOR-CONTROL MECHANISM.

Application filed May 8, 1924. Serial No. 711,858.

To all whom it may concern:

Be it known that we, RILEY M. DODD and JOSEPH A. McVAY, citizens of the United States, residing at Torrance, in the county of Los Angeles and State of California, have invented certain new and useful Improvements in Motor-Control Mechanisms; and we do hereby declare the following to be a full, clear, and exact description of the invention, such as will enable others skilled in the art to which it appertains to make and use the same.

This invention relates to a control mechanism primarily adapted as an attachment for electric motors, to enable hand control thereof as in oil well or other drilling.

The invention aims to provide a simple, compact and inexpensive construction which may be built into the motor initially or may be designed to serve as an attachment for the motor.

Additional objects and advantages will appear from a consideration of the description following taken in connection with accompanying drawings illustrating an operative embodiment.

In said drawing:—

Figure 1 is a plan view showing the control mechanism in connection with a fragment of an electric motor, and

Figure 2 is a side elevation of the parts of Figure 1.

Like reference characters designate like or similar parts in the different views.

Referring specifically to the drawing, A designates the top or fragment of an electric motor.

A motor control shaft is provided at 10 which may be an extension of the main shaft of the motor or coupled thereto for unitary rotation therewith. Rotatable with the shaft 10 is a large master gear wheel 11 which has a cylindrical hub 12 removably telescoped over the upper end of shaft 10 and fastened thereto as by a bolt or screw 13.

The hub 12 is journaled centrally of a bed plate or base 14 which is suitably connected to the top or casing of the motor A as by

means of removable bolts 15, being held at the proper elevation by spacing sleeves 16 surrounding the bolts.

At diametrically opposite points, bearings 17, preferably integral with the bed plate 14 arise therefrom and carry bushings 18 in which a controller shaft 19 is journaled. This shaft has a pinion 20 removably and rigidly fastened to it and arranged in mesh with the master gear wheel 11. A lock nut 21 is preferably removably disposed on the shaft 19 at one end thereof while at the other end, a hand wheel 22 is rigid therewith.

In use, in order to brake the speed of rotation of the motor, or reduce it or stop it, the wheel 22 is engaged by the operator's hand and appropriately manipulated whereby the shaft 19 is turned and gear wheels 20 and 11 turned, imparting corresponding control movement to the motor control shaft 10. The device provides control for the motor, independent of its control switch and aside from giving control which is impossible with a switch, avoids unduly frequent manipulation of the switch.

What is claimed is:

A motor control mechanism, in combination with a motor having a controlling shaft extending therefrom, a bed plate having an opening accommodating said shaft, a master gear wheel having a hub telescoped onto said shaft and journaled in said bed plate, bolts securing said bed plate to the motor, spacing sleeves surrounding said bolts intermediate the motor and the bed plate, bearings integral with said bed plate, a manually operable controlling shaft journaled in said bearings, a gear wheel carried by said controlling shaft in mesh with said master gear wheel, and a hand operable element for said controlling shaft.

In testimony whereof we affix our signatures in presence of two witnesses.

RILEY M. DODD.

JOSEPH A. McVAY.
